IGNITION DEVICE FOR IONIC VALVES

Uno Lamm, Ludvika, Sweden, assignor to Allmänna Svenska Elektriska Aktiebolaget, Västera, Sweden, a corporation of Sweden

Application April 10, 1947, Serial No. 740,655
In Sweden April 11, 1946

8 Claims. (Cl. 250—27.5)

1

A common kind of disturbance in ionic valves having a liquid cathode, especially in such valves having only one anode, is an extinction of the excitation anode which serves to maintain an arc spot on the cathode when no main anode is active. In rectifiers the disappearance of the cathode spot may cause a total interruption of the current, and in inverters it may cause the failure of a commutation which acts as a short-circuit if no special protective steps are taken. For restoring the cathode spot and re-igniting the excitation anode, rapidly acting re-igniting devices have been used which operate without movable parts, for instance resistance igniting devices, so-called ignitors, or capacitatively acting ones. The present invention relates to a device for bringing such igniting devices into action at the disappearance of the cathode spot, said device being very rapid and effective in action.

The invention is based on the following observation. If no cathode spot is present when a main anode normally is about to be ignited—which means either that it has just become positive or that its potential which already is positive is admitted by the grid to the conducting plasma in the neighbourhood of the cathode—the said plasma will assume a positive potential with respect to the cathode, often a rather high such potential, as the anode voltage rises without any ignition taking place. Between the conducting wall of the vessel and the plasma, there is as a rule the possibility of a vivid exchange of charges, in the first line by ion attraction and secondly by glow discharge which latter eventually may lead to the formation of a cathode spot on the wall. The latter may therefore to a certain extent follow the potential of the plasma which as aforesaid lies considerably above that of the cathode. This potential difference is, according to the present invention, utilized for feeding the instantaneous ignition device either directly or indirectly by operating a rapidly acting relay, for instance an ionic tube (thyatron). The direct feeding is generally preferable when the current between the plasma and the wall is sufficient to feed the igniting device, since the action will then be more rapid and safe. Instead of employing the wall of the vessel, other conductors in contact with the plasma may be used, as is more fully explained below.

Three forms of the invention, all arranged for a direct feeding of the igniting device, are diagrammatically illustrated in Figs. 1-5 of the accompanying drawing.

Fig. 1 shows a single anode high tension valve

2

having a cathode 1, a cathode space 2 with a conducting wall, an anode space 3 with an at least partly insulating wall, containing voltage distributing conductors 4 and an anode 5. Near the cathode, there is an excitation anode 6 which is fed from a current source 7 of comparatively low voltage, and in immediate contact with the cathode there is a resistance igniting device ("ignitor") 8 which also can be fed from a separate device 9. This device may for instance communicate to the ignitor one impulse in each cycle and may in such case act as a substitute for the excitation anode, or it may enter into action only on the occasion of disturbances. In the latter case, the device according to the present invention may act so as to reinforce the action of the ignitor which otherwise may be insufficient. The ignitor 8 is further connected to the wall of the cathode space 2 across a valve 10. It may also be connected to the cathode across an over-voltage diverter 11 for protecting the cathode insulation, as the voltage between these parts may be rather high on the occasion of a disturbance.

25 The arrangement described operates in the following manner. When the main anode 5 becomes positive and is liberated but cannot ignite on account of the absence of a cathode spot on the regular cathode, the plasma in the cathode space assumes a high positive potential. For the reasons already stated, nearly the same potential is communicated also to the wall, so that a strong current flows from this wall across the valve 10 to the ignitor 8 and thereby produces a new cathode spot.

30 The valve 10 prevents the feeding device 9 of the ignitor from influencing and from being influenced by the potential of the wall when impulses are emitted from the said device 9. If the valve 10 is composed of a sufficient number of dry valve plates for its purpose, it obtains, at the normal characteristic of the dry valves, the property that the potential difference between 35 the wall and the cathode, which is very low in normal operation, does not admit any appreciable current and is thus not loaded nor loads the ignitor. If the device 9 is omitted and the ignitor 8 is only fed from the wall, the valve 10, 40 which may be regarded as a voltage-dependent resistance of directional character, may as shown in Fig. 4 be replaced by a voltage-dependent resistance 42 without any directional character, the ohmic value of which decreases with 45 increasing voltage. In certain cases it may con-

sist of an ionic valve. The igniter may also be of a capacitatively acting character.

Instead of deriving the ignition impulse from the potential difference between the wall of the vessel and the cathode, it may also be derived from a conductor inside the vessel of the character of a probe which also may serve other purposes. Figs. 2 and 3 show example hereof.

Fig. 2 shows a single-anode valve vessel for comparatively low voltage having a cathode 16, anode 17, anode sleeve 18, excitation anode 19 with a current source 20 and an ignitor 21 with a feeding device 22. In this form, the ignitor 21 is connected across a valve 23 to a probe 24 mounted between the mouth of the anode sleeve and the cathode, said probe being especially constructed for following the potential of the plasma as closely as possible, for instance provided with points or coated with an electron emissive substance, and further it may be provided with a heating device or so placed as to be heated by the surroundings, whereby it will to a certain extent obtain the character of a hot cathode. It may at the same time serve as a screen for protecting the anode against direct radiation from the cathode.

Fig. 3 shows a polyanodic valve vessel having anodes introduced through the bottom. The cathode is designated by 31, the anodes by 32 and the anode sleeves by 33. The excitation anode with its current source is not shown. In polyanodic vessels, it may be advisable to employ a separate conductor or probe for each anode for rapidly absorbing the higher potential which the plasma in the neighbourhood of the anode obtains when the cathode spot is extinguished. The anode sleeve itself or a member in the immediate neighbourhood thereof may be employed. Each such member may be connected to the ignitor 35 by a separate valve 34. The figure shows the anode sleeves connected in this manner. Instead of using these sleeves as probes, an insulated screen 36 which covers the lower ends thereof and possibly the bottom of the vessel may serve the same purpose.

Fig. 5 shows another form utilizing a thyratron 37, the grid of which is connected to the wall of the valve vessel through a voltage source 38. Between the anode of the thyratron and the cathode of the main vessel is arranged a voltage source of a type which gives only short impulses. Such a source is used because, as is well known, a thyratron circuit cannot be interrupted by grid control only and with a different type of source it would be difficult to break the igniter circuit after it was once established. The preferred source is a condenser 39 charged from a voltage source 40 through a high ohmic resistance 41 and discharged through the thyratron.

I claim as my invention:

1. In ionic valves having an arcing cathode, an instantaneously acting igniter permanently adjacent to said cathode, a conductor insulated from said cathode and in contact with the ionized plasma occupying a current path of said valve, means, controlled by a potential difference between said conductor and said cathode, for forcing a current through said igniter, and means preventing a flow of current from the cathode to said conductor.

2. In ionic valves having an arcing cathode,

an instantaneously acting igniter in contact with said cathode, a conductor insulated from said cathode and in contact with the ionized plasma occupying the current path of said valve, a leading connection between said conductor and said igniter, and means preventing a flow of current from the cathode to said conductor.

3. In ionic valves having an arcing cathode, an instantaneously acting igniter in contact with said cathode, a conductor insulated from said cathode and in contact with the ionized plasma occupying the current path of said valve, and a connection including a voltage dependent resistance between said conductor and said igniter.

4. In ionic valves having an arcing cathode, an instantaneously acting igniter in contact with said cathode, a conductor insulated from said cathode and in contact with the ionized plasma occupying the current path of said valve, a device for regularly feeding said igniter, and a common connection, including a substantially unidirectionally conducting valve, leading from said conductor to said device and said igniter.

5. In ionic valves having an arcing cathode, an instantaneously acting igniter in contact with said cathode, a conducting wall insulated from said cathode and surrounding the space adjacent to said cathode, and a leading connection between said wall and said igniter.

6. In ionic valves having an arcing cathode, an instantaneously acting igniter permanently adjacent to said cathode, a conductor screening different internal spaces of said valve from each other, and insulated from said cathode, means controlled by a potential difference between said screening conductor and said cathode, for forcing a current through said igniter, and means preventing a flow of current from the cathode to said conductor.

7. In ionic valves having an arcing cathode, an instantaneously acting igniter permanently adjacent to said cathode, a conductor screening the space adjacent to an anode of said valve from other conducting spaces thereof, means controlled by a potential difference between said conductor and said cathode for forcing a current through said igniter, and means preventing a flow of current from the cathode to said conductor.

8. In ionic valves having an arcing cathode, an instantaneously acting igniter permanently adjacent to said cathode, a conductor insulated from said cathode occupying a current path of said valve, means for facilitating the exchange of electrons between said conductor and the ionized plasma, means, controlled by a potential difference between said conductor and said cathode, for forcing a current through said igniter and cathode, and other means for independently forcing a current through said igniter and cathode.
